PLASTIC COATED FABRIC OR SIMILAR ARTICLE

Jakob H. Vogel, 110 Longview St., West Orange, N.J.

Filed Sept. 17, 1959, Ser. No. 57,584

Term of patent 14 years

(Cl. D87—3)

The figure is a plan view of a plastic coated fabric or similar article showing my new design, the repeat unit of which is substantially contained between the two horizontal dot and dash lines and the two vertical dot and dash lines.

This application is a continuation-in-part of my co-pending application, Serial No. D. 49,646, filed February 14, 1958.

I claim:

The ornamental design for plastic coated fabric or similar article, as shown and described.
